UNITED STATES PATENT OFFICE.

OSCAR SODERSTROM, OF NEW YORK, N. Y., AND WARREN FUHRMANN, OF WESTFIELD,
NEW JERSEY.

MACHINE FOR MAKING SNAP-FASTENERS.

1,340,634.

Specification of Letters Patent. Patented May 18, 1920.

Application filed April 14, 1917, Serial No. 162,156. Renewed October 20, 1919. Serial No. 332,101.

To all whom it may concern:

Be it known that we, OSCAR SODERSTROM, a citizen of the United States, and a resident of New York city, county of Bronx, 5 and State of New York, and WARREN FUHRMANN, a citizen of the United States, and a resident of Westfield, county of Union, and State of New Jersey, have invented certain new and useful Improvements in Machines 10 for Making Snap-Fasteners, of which the following is a specification.

This invention relates to means for forming the headed parts of the form of buttons known as resilient head and socket devices, 15 and designed to produce the complete finished head from a strip of sheet metal, by successive die operations.

The object of the present invention is to provide means for forming a device in the 20 nature of a flat base with a slender neck and enlarged head of spherical form, by the process of first forming a cylindrical extension on the blank with the upper closed end preferably rounded, and thereupon holding 25 the lower portion of the neck from changing its shape while exerting a downward pressure on the upper end to cause expansion of the metal to form the head.

A further object of the invention is to 30 provide means for holding the lower portion or base of the blank during the formation of the head.

In the accompanying drawing showing 35 one embodiment of our invention Figure 1 is a vertical section through the device with the plunger elevated. Fig. 2 is a similar view with the plunger in the lowered position. Fig. 3 is a cross section on the line 3—3 of Fig. 1. Fig. 4 is a similar view 40 with the plunger partly lowered and Fig. 5 is a similar view with the plunger in the lowermost position. Fig. 6 is a plan view of the bed showing certain parts in section; and Fig. 7 is a view enlarged of the 45 arms for holding the neck of the blank.

As shown the device comprises a plunger 8 and a bed denoted generally by 9. At the left hand end of these members are dies for 50 acting on the blank to form a cylindrical extension with a closed upper end. These may be of any desired construction, and as shown comprise a set of punches 10 that enter sockets in a die block 11 attached to the plunger. These are graded in thickness and 55 length to produce an extension 12 in five

different operations, it being understood that the strip 13 is advanced between each descent of the plunger, for a distance equal to the distance apart of the dies. Such mechanism forms no part of the present invention, but is a part of the apparatus to produce the preliminary forming of the blank or extension. 60

After the blank is advanced the extensions 12 pass along the bed plate 14 between a pair of arms 15 and 16 that are laterally moved toward the blank. These arms have slots 17 and 18 in their opposite faces adapted to form a cylindrical bore when brought together, substantially of the form of a blank extension 12. The arms at this portion are caused to engage the extension 12 adjacent the base of the strip 13, with a considerable portion of the extension projecting above these arms. The slots in these arms are recessed at the upper portions as shown at 19. By this arrangement when the arms are brought together to engage the neck the recessed portion will form a kind of cup shaped space at the upper part of 80 the arms.

A die block 20 is carried by the plunger 8 and has a recess 21 in its lower face that when the plunger is brought down will strike the extension 12 of the blank. Since 85 the blank is supported at the lower portion of the neck, the part projecting above the arms will not be supported and will tend to expand. This recess is so shaped that it together with the cup shaped recessed portion 90 of the arms would form a kind of spherical die that will cause the upper end of the extension to assume a spherical head or like formation, as indicated in Fig. 5.

These arms are automatically caused to 95 approach and engage the blank by means of bars 22 and 23 carried by the plunger, that engage cam faces 24 and 25 on the arms respectively. These bars will cause the arms to approach and clamp the extension, and then the bars will pass below the cam faces at the end of the arms and retain the arms engaging the extension. When the plunger rises and the bars free the arms, springs 26 and 27 will serve to cause recession of the 105 arms.

Means are further provided to support the extension at its base during the head forming operation. As shown we provide a plunger block 28 slidable in the bed and 110

normally retracted by a spring 29. A slide 30 moves through a slot in the block and has a wedge face 31 engaging the inclined upper face 32 of the slot, so that when the 5 slide is advanced the block will be raised. The slide has a beveled end 33, that is engaged by the beveled end 34 of a bar 35, fast to the plunger 8. Therefore descent of plunger will advance the slide and elevate 10 the block 28 that is provided with a curved lug 36 that is caused to enter the base of the extension on the lower face of the strip, and serves to support the extension when engaged by the arms and the descending 15 plunger 20. When the plunger is retracted a spring 37 will retract the slide 30, permitting withdrawal of the block 28 by its spring 29.

It will thus be seen that when the plunger 20 descends the laterally movable arms are first brought to engage the extension 12 on the blank at the base thereof, and thereupon the block 28 is elevated to engage the base of the extension on the lower face. These 25 parts are rigidly held in this position and the die block 20 is brought down to engage the upper end of the blank extension. This would tend to depress the extension, but being held at the bottom and at the sides of 30 the base, the blank is forced to expand as it is moved downwardly and hence must assume the shape of a head, as shown in Fig. 5. It will be seen that the upper half of this head lies in the recess 21 of the die 35 block, that is substantially hemi-spherical. The lower portion of the head is formed in the upper recessed portion of the slots of the arms.

The blank is thereupon advanced in the 40 strip, to be later severed therefrom by cutting dies such as indicated at 38 and 39. If desired the blank can be perforated by dies 40 and 41. Also the blank could be embossed by suitable dies 43 and 44 before the 45 final severing of the blank to form the completed button head.

Having thus described our invention, what we claim is:—

1. A sheet metal shaping apparatus comprising a bed, a plunger movable to and from the bed, a pair of laterally movable arms on the bed, said arms having their opposite ends arranged to engage and clamp the cylindrical neck of a blank, means for causing approach of said arms to clamp the neck on the initial downward movement of the plunger, a recessed die on the plunger arranged to engage the top of the blank at the latter portion of the descent of the plunger after the clamping of the neck by said arms to cause the end of the neck to expand

to form a spherical head, a block located below the cylindrical portion of the blank engaged by the arms, and means actuated on descent of the plunger to elevate said block 65 to engage the base of the blank and support it on descent of the plunger and die.

2. A sheet metal shaping device comprising a bed, a plunger movable to and from the bed, a pair of laterally movable arms on the bed, said arms having their opposite faces arranged to engage and clamp the cylindrical neck of a blank, springs arranged to separate said arms, bars on the plunger arranged to engage said arms to advance 70 them to engage the blank and retain them in engaging position on further descent of the plunger, a die on the plunger arranged to engage the top of the blank on descent of the plunger after said movement of the arms 75 to engage the blank, a block located in the bed arranged to engage the lower face of the cylindrical blank when advanced, a slide arranged to advance said block, and an arm on the plunger arranged to engage 80 said slide to raise the block to engage the blank on descent of the plunger, to hold the block in raised position.

3. A sheet metal shaping device comprising a bed, a plunger movable to and from 90 the bed, laterally movable arms on the bed arranged to be brought together to clamp the neck of a blank, a die on the plunger arranged to engage the top of the blank, means for actuating the plunger and said 95 arms to cause descent of the plunger after approach of said arms, a supporting member for the blank, and means controlled by said actuating means to elevate said support on descent of the plunger to hold the support elevated on engagement of the said plunger die with the blank.

4. A sheet metal shaping device comprising a bed, a plunger movable to and from the bed, arms movable to engage the neck of 105 a cylindrical blank, a die carried by the plunger, actuating means for the plunger and arms to cause descent of the plunger after the arms engage the blank, a support having a movable portion arranged to engage the cylindrical portion of the blank at the base, said support having its lower face inclined, a slide having an inclined face and laterally movable to engage and raise the support, a spring for retracting the slide, 110 and an arm on the plunger having an inclined face arranged to engage and advance said slide on descent of the plunger whereby 115 to raise said support.

OSCAR SODERSTROM.
WARREN FUHRMANN.
